CARD FEEDING MECHANISM

Elmer H. Grogan, Danville, Ill.

Original application February 26, 1945, Serial No. 579,719. Divided and this application September 7, 1945, Serial No. 615,003.

6 Claims. (Cl. 271—30)

1

This application is a division of my co-pending application Serial Number 579,719, filed February 26, 1945, now Patent No. 2,426,092, issued Aug. 19, 1947.

This invention relates to an apparatus for feeding articles such as sensitized cards to machines for printing photographs in large quantities from a single negative, group of negatives or plate.

The machine is automatic and requires a minimum of attention. It is a feature of the improvements that the apparatus can be adjusted to synchronize the feeding of the cards with the various other operations which must be performed in the course of the printing step, including feeding the card, exposing it, and releasing it from the machine. Numerous machines have been used for this purpose, but they are subject to disadvantages which have been eliminated or minimized by my present improved machine.

It is an object of my invention to provide a bulk supply of sensitized cards at a point from which these cards may be automatically picked up and supplied to an exposure or printing zone.

The invention is illustrated and may be understood by reference to the accompanying drawings.

Figure 1 is a perspective view partly in section of a photo-printing machine, the view being from the left and front thereof.

Figure 2 is a view in perspective partly in section of the card magazine and pickup mechanism, and the parts by which these various elements are driven. It is taken from the right and front of the machine, i. e., the side opposite that shown in Figure 1.

Referring to Figure 1, a container or magazine for holding a bulk supply of cards 11 is indicated at 10. It should be noted that this box is placed at an angle out of the perpendicular so that the cards 11 will tend to remain in a compact mass by their own weight. The cards are held in position and forced toward the front of the magazine by a follower 12. (See Fig. 2.) The follower is moved by means of the automatic mechanism illustrated in Fig. 2. This mechanism comprises a shaft 13 driven by pulley 14, which in turn may be driven by a belt passing around a pulley 14' on the main power shaft. Two pulleys of different diameter may be provided to change the speed of the follower to compensate for the use of single or double weight sensitized cards which differ in thickness. The shaft 13 may be supported on the main body of the frame by means of an adjustable support 15. The corresponding support at the opposite

2

end of shaft 13 and brackets for supporting the magazine are not illustrated in interests of simplification. Shaft 13 is journaled in bearing 16, which is supported by bracket 17. When pulley 14 is driven, shaft 13 turns worm 18, driving pinion 19, thereby turning threaded shaft 20 which is journaled in brackets 21 and 22, which in turn are fastened to the frame of bulk supply box 10.

Supported on shaft 20 is a threaded member 23 which is attached to a bracket 24 which in turn passes through a slot in the side of box 10 and is attached to follower 12. Member 23 comprises threaded jaws, not illustrated, at the respective ends of wings 25 and 26 which are pivoted at 27. The wings are held apart by a spring under compression so that the threads on the jaws are kept in mesh with the threads on shaft 20. The jaws can be released by compressing wings 25 and 26 and the follower 12 may be shifted from one position to another along shaft 20. This permits the operator to refill the box by merely releasing the jaws of member 23 and sliding the entire assembly to the back of the box and then placing the cards in position in front of the follower. The operator can adjust the position of the follower to its proper place by moving it along shaft 20 until the bulk supply of cards have been pushed firmly against wings 28 and 29 at the forward end of the magazine and thus properly located to be fed in a manner hereinafter described. A wing corresponding to 28 is located on the other side of the box. These project just enough to prevent the cards from falling out of the box, especially when the pickup mechanism is operating.

The entire magazine is tilted backward so that the cards will be in proper position to be picked up by the mechanism about to be described. There is an additional advantage that the cards tend to stay packed even when the follower is released, which is important with sensitized cards. When the foremost card is picked up by means of the suction pickup apparatus, it is bent slightly at the sides and bottom as it passes these projections 28 and 29 so that a positive pulling action must be exerted to remove it. Thus it is assured that only one card at a time can possibly be fed to the feeding chute. This is a marked advantage over other feeding devices using mechanical feeders. If anything happens to the pickup mechanism no cards are fed. A condition can never exist in which more than one card is fed at one time.

The cards are picked up by means of suction cups 30, which are attached to vacuum lines 31.

The suction cups are made of rubber or other resilient material. The vacuum lines are rigidly secured in rocker arm 32. The position of the suction cups may be adjusted by sliding the lines forward or backward in the journal 33 passing through bracket 32. After the position has been properly adjusted, they may be held by means of set screws or other suitable means.

During operation, the suction cups 30 press against the foremost card in the box due to the forward motion of arm 32. At this moment, lines 31 are evacuated by opening valve 31' from a suitable vacuum source. Vacuum sufficient is supplied to hold the foremost card firmly and to pull it out of the box as arm 32 moves away from box 10. When the arm has traveled far enough to pull the card past wings 28 and lip 29, the vacuum valve closes and the pressure in line 31 is restored to atmospheric through a relief valve. A cam on shaft 45 operates the valve 31'.

The card no longer being held by vacuum cups 30 is released and drops down the chute. A tapered hopper comprising sidewalls 34' and vertical guide wings 34 leads the dropped card into chute 35. In order to prevent the card from falling out of the chute, guide wings 34 are placed parallel to the feeding chute 35, which likewise is equipped with wings to guide the card during its downward fall into proper position for later operations to be performed upon it. Also, to assist in this operation and to be certain that the card falls into its proper position, the machine is preferably tilted slightly to one side or the other by setting the mechanism at an angle. As illustrated in the drawing, the machine is tilted to left so that the card tends to slide along the left hand side of the chute. The chute 35 is otherwise substantially vertical except that it leans to the left. If there is any slope, it should be such that the card will rest along the back of chute 35 as it falls, for example by raising the front of the machine slightly or building it with a slight pitch toward the rear.

Reciprocating arm 32 is keyed to a shaft 36 which is journaled in a bracket 37 attached to the frame of the machine. Also keyed to shaft 36 is arm 38 which is shaped to conform to a cam 39. The cam in turn is keyed to a shaft 40 which is supported pivotally in brackets 41 attached to the frame of the machine. Shaft 40 is rocked back and forth by means of rocker arm 42 rigidly attached to shaft 40 and pivotally attached to link 43, which in turn is pivoted to bell crank 44 which is driven from the main power shaft 45, and as illustrated, is journaled in bracket 46 attached to the frame of the machine. When the bell crank 44 is revolving, it imparts a reciprocating motion through link 43 and arm 42 to cam 39, which in turn imparts a rocking motion to arms 38 and 32. Thus with each revolution of bell crank 44, the suction cups 30 move forward to pick up a card and then move backward into position to drop the card down the chute 35. It is in this manner that the cards are fed one at a time down the chute.

The pitch of the threads on shaft 20 and member 23 are such that the follower 12 is moved forward a distance equivalent to the thickness of one card during each revolution of shaft 45. The size of pulley 14 is chosen depending upon the thickness of the card used, or as before mentioned, a second pulley of different size may be placed on the shaft so that a quick change can be made merely by shifting the belt. This permits a change in the speed at which shaft 20 is rotated,

and consequently the speed at which follower 12 moves along the supply box.

Spring 47 is attached to the frame and to arm 32 in order to pull it forward when the cam 39 is in position for the cards to be picked up.

The rocking motion imparted to shaft 40 likewise imparts a rocking motion to arm 48, which is keyed to shaft 40 and to link 49, which is pivoted to arm 48 which actuates the mechanism for stopping and releasing the cards, exposing them and finally discharging them. The illustrated apparatus is fully described in the above mentioned patent application and its operation is synchronous with that of the card feeder.

The above described and illustrated device is one preferred form of the invention but it is not intended to be limited exactly to the form shown.

I claim as my invention:

1. A card feeding device comprising in combination, a support, a main drive shaft mounted thereon, a second drive shaft, power transmission means from said main drive shaft to said second shaft, a threaded shaft mounted for rotation, speed reducing gearing on said second shaft and said threaded shaft thereby to drive the latter at a reduced speed, a card magazine having an opening in the front thereof for removing cards, a hopper mounted in front of said opening, a card follower mounted in the magazine, adjustable threaded means mounted on said follower operatively engaging said threaded shaft thereby to advance said follower in the magazine when said shaft is rotated, a bell crank fixed to said drive shaft, a rocker arm, a link connecting said bell crank and said arm thereby to impart rocking motion to the latter, a rocker shaft fixed to said rocker arm, a cam attached to said shaft, a cam follower operatively engaging said cam, a second rocker shaft attached to the cam follower thereby to receive rocking motion, a vertical arm attached to the second rocker shaft, a vacuum cup attached to said vertical arm, said cup being spaced from the arm and mounted in front of the opening in the magazine, said cup receiving reciprocating motion toward and away from said opening when said vertical arm is moved due to the motion of the second rocker shaft, a duct connecting said cup with a source of vacuum, means synchronous with the movement of said drive shaft to alternately evacuate the cup when in position to contact a card in the opening in said magazine and to release the vacuum when the cup is away from the opening, thereby to remove a card from the magazine and release it into the hopper; said combination arranged and adapted so that said vacuum cup reciprocates once for each rotation of said main drive shaft, and said card follower is caused to advance a distance corresponding to the thickness of one card for each such rotation.

2. A card feeding device comprising in combination a card magazine, a main drive shaft, a device for maintaining cards in pick up position in the magazine, card pick up means, both of the latter synchronously actuated by said drive shaft, said card maintaining device comprising a threaded shaft, speed reducing power transmission means operatively connecting said drive shaft and said threaded shaft, a card follower, threaded means attached to the follower engaging the threaded shaft whereby to advance said follower a distance equal to the thickness of one card for each revolution of the drive shaft, means whereby said threaded means may be adjusted to engage said threaded shaft at any point over its length; said card pick up comprising a bell crank

attached to said main drive shaft, a link pivotally attached to the crank, a rocker arm attached pivotally to the link, a first rocker shaft fixedly attached to the arm, a cam fixed to the rocker shaft, a cam follower operatively engaging said cam, a second rocker shaft fixedly attached to said cam follower thereby to receive rocking motion, a pickup arm fixed to the second rocker shaft, a vacuum cup attached to said pickup arm and spaced therefrom toward said magazine, said cup receiving reciprocating motion toward and away from the magazine when the pick-up arm rocks; means for mounting said follower in said magazine, a card removal opening at one end of said magazine, said opening being slightly smaller than a card to be held in said magazine, a hopper in front of said opening, said hopper opening into a duct into which said card is to be dropped, guides to lead said card into said duct, said vacuum cup mounted directly in front of said opening in position to contact a card therein at the forwardmost position, and to release such a card into the hopper in its position farthest from the opening, duct means connecting said cup with a source of vacuum, valve means in said duct controlled by the movement of said drive shaft to supply vacuum at the forwardmost position of the cup to pick up a card, and to release the vacuum at a position remote from the magazine to drop said card into the hopper.

3. The apparatus of claim 2 wherein the speed reducing transmission comprises a worm gear.

4. The apparatus of claim 1 wherein the magazine is tilted with the opening at the higher end.

5. The apparatus of claim 1 wherein the magazine is tilted with the opening at the higher end, and also tilted to one side.

6. The apparatus of claim 1 wherein the threaded shaft is supported externally on one side of the magazine, the magazine is slotted parallel with the shaft, and the adjustable threaded means attached to the follower extends through said slot to operatively engage the shaft.
